Primary Examiner—Holly H Baynham*Assistant Examiner*—Sheryl Lane(74) *Attorney, Agent, or Firm*—Calfee, Halter & Griswold LLP(57) **CLAIM**

I claim the ornamental design for a face plate, as shown and described.

DESCRIPTION

FIG. 1 is a front perspective view of a face plate of the new design, showing the face plate installed on an exemplary storage box;

FIG. 2 is a left side perspective view of the face plate of FIG. 1;

FIG. 3 is a front elevation view of the face plate of FIG. 1;

FIG. 4 is a top view of the face plate of FIG. 1;

FIG. 5 is a rear view of the face plate of FIG. 1;

FIG. 6 is a right side view of the face plate of FIG. 1;

FIG. 7 is a left side view of the face plate of FIG. 1; and,

FIG. 8 is a bottom view of the face plate of FIG. 1.

The portions of the Figures shown in phantom lines form no part of the claimed design and are either for illustrative purposes only, or to define the bounds of the claimed design.
